(57) **CLAIM**

The ornamental design for a golf glove, as shown and described.

DESCRIPTION

FIG. 1 is a back thumb-side perspective view showing our new design;

FIG. 2 is a view of the back thereof;

FIG. 3 is a view of the front thereof;

FIG. 4 is a thumb-side view thereof;

FIG. 5 is a small-finger-side view thereof;

FIG. 6 is a view of the closed fingertip end thereof; and,

FIG. 7 is a view of the open wrist end thereof.

In FIGS. 1-7, the short broken lines represent stitching and form no part of the claimed design, the long broken lines represent unclaimed portions of the glove and form no part of the claimed design. The different shading shown in regions of the back and regions of the front thereof indicates a contrast in appearance between the respective regions.
